PRINTING MACHINE

Henry E. Hubbard, La Grange, Ill., assignor to
Addressograph Company, Wilmington, Del., a
corporation of Delaware

Application May 4, 1931, Serial No. 534,797

39 Claims. (Cl. 101—47)

This invention relates to printing machines of the kind used for printing bills, statements, notices, and the like which have a permanent form printed thereon in the machine or prior to introduction of the sheets into the machine. These machines are used to print variable data in the nature of addresses or the like on the sheets. Additional variable data are often printed on the sheets and this has been done in another printing machine. For example, in printing bills, the addresses are printed in one machine while the numerical data, such as the prices and extensions thereof, are printed in another machine as, for example, in a computing printing machine. Further, when notices are printed it is often desirable to not only print the permanent form and the address but also to print additional information as, for example, the name and address of an agent or the like. The additional data are related to the addresses and might be provided on the device used for the printing of the addresses were it not for the fact that this additional data vary on successive uses of the printing devices as different sets of sheets are printed. The salient object of my invention is to provide a machine wherein variable data, such as addresses or the like, may be printed on sheets passing therethrough and wherein additional variable data related to the first variable data may likewise be printed on the sheets.

Another object is to provide a machine wherein related but independent variable data may be printed on the sheets during passage thereof through the machine from separate printing devices.

Further objects of the invention are to provide a machine wherein a corresponding number of repetitive printing impressions may be made from the separate printing devices; wherein the number of repetitive printing impressions performed on the sheets may be varied; wherein the sheets will be oriented relative to the printing devices so that impressions may be made thereon at predetermined places; and which will be simple and positive in operation and economical in manufacture.

In the selected embodiments of my invention illustrated in the accompanying drawings,

Fig. 15 is a detail view taken substantially on the line 15—15 on Fig. 11.

In the embodiment of the invention illustrated in Figs. 1 to 10, inclusive, 16 indicates the frame of a printing machine having the usual table top 17 on which printing operations are performed on

sheets S stored in a rack T from which they are withdrawn by movable suction nozzles 18 to be passed between the feed rollers 19 and 20 and thence to a traveling belt conveyor 21 which carries the sheets across the table top 17 below

the platen P. The platen is operated from the shaft 22 driven from the shaft 23 connected to the flywheel 24 in the manner disclosed, for example, in the application of Walter T. Goilwitzer, Serial No. 391,141, filed September 9, 1929, now

Patent No. 1,900,281, patented March 7, 1933. The flywheel is driven by the belt B which is operated from the pulley C mounted on the shaft 24.

Power is supplied to the shaft 24 from the motor M through the belt N to the pulley Q fast on the shaft 24. Also driven from the shaft 23

in the manner described in the referred to application is a cam shaft 25 having cams 26 thereon. Mounted in juxtaposition to the cam shaft is a

shaft 27 having a plurality of bearings 28 thereon. These bearings 28 carry stop fingers 29 and tail portions 30 which have rollers thereon that engage the cams 26. The cam shaft 25 is operated in timed relation with the platen operating

shaft 22 and serves to successively move the

fingers 29 into the path of the sheets traveling on the belt conveyor to stop the sheets during the time the platen is making an impression through the ink ribbon R from the printing device D moved into position below the platen by the usual printing device feeding means 31.

If, for example, the sheet being printed is a public utility bill, including a main body and one or more stubs, the stop fingers will be spaced so that the sheet will be stopped in positions wherein the platen P will make an impression from the printing device D on each of the stubs and on the main body. The sheets S stored in the rack T have a permanent form printed thereon prior to storage in the rack but the sheets may be severed from a web and the permanent form may be printed thereon in a machine like that disclosed, for example, in the application of Emmett C. Hartley, Serial No. 404,123, filed November 1, 1929, now Patent No. 1,955,306, patented April 24, 1934, as my invention may be used with a machine of this kind.

A machine constructed in accordance with either of the referred to applications so prints a sheet that it will have an address thereon as well as a permanent form but the printing of any other matter on the sheet has been performed in a separate machine. Impressions are made from the printing devices D on the main body and each of the stubs, and it is desirable that any additional data printed on the sheets be likewise printed on the main body and each of the stubs. In the present machine, after an impression has been made from the printing device D on the last section of the sheet the printing device feeding means is rendered operative and a new printing device D is moved into position below the platen P and consequently impressions will be made therefrom onto the succeeding sheet moving with the traveling belt conveyor, and these printing operations will be performed in the manner just described.

The printing device feed used herein may be one like that disclosed in the application of Walter T. Gollwitzer, Serial No. 497,433, filed November 22, 1930. As described in that application the printing device feed mechanism is operated from the platen operating shaft and in the present instance an eccentric 185 is fast on the shaft 22 and is surrounded by a band 186 embodying a portion 187 to which one end of a plunger 188 is secured. Fast on the plunger 188 is a collar 189. The plunger 188 extends through a sleeve 190 having a bearing 191 thereon pivotally connected at 192 to an arm 193 unitary with the drive rocker 95 that is pivotally mounted on shaft 22. A latch 194 is pivotally mounted at 195 on the sleeve 190 and includes a shoulder 196 that is normally urged into engagement with a surface on the collar 189 by a spring 197 acting on the latch 194. On the latch 194 is a pin 198 engageable with a cam surface 199 on the arm 193 of the rocker 180 pivotally mounted at 181. On the other arm 182 of the rocker 180 is a roller 183 engageable with a cam 184 fast on the cam shaft 25. As the shaft 22 rotates, the eccentric 185 is rotated and a reciprocating movement is imparted to the plunger 188. So long as the shoulder 196 engages the collar 189, the sleeve 190 and the plunger are latched together and the sleeve reciprocates with the plunger 188 and the reciprocating movement imparted to the sleeve 190 is transmitted to the arm 193. The arm 193 is unitary with the drive rocker 95. A pawl 170 is pivotally mounted at

the free end of the drive rocker 95 and includes a recessed nose portion 171 engageable with the pins 172 on the sprocket 173 about which a printing device feed chain is directed, the sprocket 173 being fast on a shaft 174 which carries a similar sprocket about which another feed chain is directed. Pawls are provided on the feed chains which engage the printing devices D to move these printing devices through the printing device guideway. As the rocker 95 rocks about the shaft, the recessed nose portion 171 successively engages the pins 172 and imparts a step-by-step movement to the sprocket 173 and shaft 174 and consequently a step-by-step movement is imparted to the printing device feed chains and therefore the printing devices are moved through the machine in a step-by-step manner.

However, unless a one-section sheet is being printed it is desirable to hold a printing device in printing position until as many impressions are made therefrom as there are sections on the sheet being printed. The ratio of operation between the platen shaft 22 and the cam shaft 25 is equal to the number of sections on the sheets being printed. The cam 184 is provided with a dwell which engages the roller 183 and acts to hold the cam surface 199 in a position such that the pin 198 is engaged and the shoulder 196 is disengaged from the collar 189 and consequently even though the plunger 188 repeatedly reciprocates, the sleeve 190 and hence the drive are not reciprocated and the printing devices are not advanced. However, when a formed portion on the cam engages the roller 183 the cam surface 199 is so positioned that it disengages the pin 198 and therefore the shoulder 196 moves into latching engagement with the collar 189 and the sleeve 190 is latched to the plunger 188 and movement is imparted to the printing device feed mechanisms to advance the printing devices. It is therefore apparent that a printing device D is held in printing position until an impression has been made therefrom by the platen P on each section of a sheet being printed.

An object of my invention is to print on the sheets variable data related to the data printed thereon from the printing devices D. To attain this I provide another printing couple in the machine which will operate on the sheets after an impression has been made on the last section thereof by the platen P. The additional data are to be printed on each section of the bill and to permit this I provide sheet stopping means similar to that previously described, and this means includes bearings 28' fast on the shaft 27 and including stop fingers 29' and tail portions 30' carrying rollers engaged with the cams 26' fast on the cam shaft 25.

The additional printing couple is mounted on the frame 16 and includes the bracket 32 on which a platen arm 34 and an inker arm 35 are pivotally mounted. These arms cooperate to provide what is substantially a jaw. At the free end of the arm 34 is the platen P'. A frame, generally indicated by 36, is mounted at the free end of the arm 35. On the frame 36 are side plates 37 and 38 having shoulders at the upper ends thereof engaging the peripheries of the bearings 39 and 40 fast on the shaft 41. Associated with the bearings 39 and 40 are wheels 42 and 43 which travel on the trackways 44 and 45 in the frame 36. Outwardly of the wheel 43 on the bearing 40 is a gear 46 meshed with a rack 47 carried by the frame 36. When the wheels 42 and 43 are moved along the trackways

44 and 45 the gear 46 rolls on the rack 47 and causes rotation of the shaft 41 and the ink transferring roller 48, rotatable about but frictionally engaged with the shaft 41 intermediate 5 the wheels 42 and 43. Between the wheel 42 and the roller 48 is an arm 49 and between the roller 48 and the wheel 43 is an arm 50, both these arms being carried by the shaft 41. At the upper end of the arms 49 and 50 is a shaft 51 10 carrying an ink applying roller 52. Depending from the table top 17 is a bracket 54 having an ink pad 55 thereon against which the roller 41 may bear to pick up ink therefrom and the ink thus picked up is carried by the roller 48 to the 15 roller 52 which applies it to the printing form.

Since the platen P' is to operate in timed relation with the stop fingers 29, I provide means for operating this platen from the platen shaft and this means includes a beam 56, one end of 20 which is slidably mounted in the upper end of the bracket 32 and at the opposite end thereof there is a yoke 57 through which the platen shaft 22 is extended. A spring 58 extends between the yoke 57 and the frame 16 and urges the beam 56 25 toward the platen shaft. On the yoke is a roller 59 engageable by a cam 60 fast on the platen shaft 22 and when the cam engages the roller, the yoke and beam are moved against the action of the spring 58. To perform a printing operation, 30 the jaw comprising the arms 34 and 35 is closed to move the platen P' and the ink applying roller 52 toward each other. This operation is performed from the beam 56 and is brought about by the following means: Extending between the 35 beam and the arm 34 is a link 61 and a link 62 extends between the arm 35 and the beam. When the link 61 is in normal position, illustrated in dotted lines in Fig. 3, it extends at an angle to the vertical. When the beam 56 is moved in a 40 direction away from the platen shaft, the link 61 is moved into vertical position and therefore the distance between the arm 34 and the beam 56 is increased and consequently the arm 34 is pivoted downwardly from the dotted line position of Fig. 3 into the full line position thereof. The 45 link 62 is at an angle to the vertical when in normal position, shown in dotted lines in Fig. 3, and when the beam 56 is moved as above described, the angularity thereof is increased, thus 50 decreasing the distance between the arm 35 and the beam 56 which causes the arm 35 to be pivoted upwardly from the dotted line position of Fig. 3 into the full line position thereof. When the cam 60 disengages the roller 59, the spring 58 55 moves the beam 56 in the opposite direction and the arms 34 and 35 are moved back into the dotted line position of Fig. 3. The foregoing movements of the arms 34 and 35 move the inking roller into engagement with the printing form 60 and also cause operation of the platen.

The roller 49 transfers ink from the pad 55 to the roller 52, and this is brought about by moving the parts carried by the shaft 41 relative to the frame 39. Extending horizontally from the arms 49 and 50 are fingers 63 and 64 to which one end 65 of the arm 65 is joined, the opposite end of this arm being pivotally connected at 66 to the lower end of a rocker 67 pivotally mounted at 68 on the bracket 69 carried by the frame 16. On the link 70 70 is a roller 70 engageable with a cam 71 fast on the shaft 22 and disposed opposite to the cam 60, said roller being held in engagement with said cam by the spring 72 extending between the bracket 69 and the rocker 67. Since the cam 71 75 is arranged opposite to the cam 60 the roller 70

will be engaged by the rise thereon at the same time at which the rise on the cam 60 engages the roller 59 to move the beam 56. Therefore, as the arm 35 is moved upwardly, the arm 65 will be moved horizontally to similarly move the parts carried by the shaft 41. Due to the intermeshing of the gear 46 with the rack 47 the shaft 41 will be rotated during this movement and the ink picked up from the pad 55 will be transferred to the roller 52. The roller 52 moves upwardly with the arm 35 and moves horizontally with the arm 65 and after the roller 52 moves downwardly the horizontal movement again takes place, but in the opposite direction with the result that the roller 52 moves in a rectangular orbit. In the movement of this roller in the upper horizontal face of the orbit, the printing form is inked and the printing operation is performed.

A stencil printing form is employed herein and these stencils are mounted over openings in a web W and are successively moved in a step-by-step manner into printing position and while the stencils are shown as being arranged over openings in a web it is within the purview of my invention to employ a web of stencil paper and to form the printing characters thereon and to do this entails the use of stencil paper of sufficient strength to resist the stresses attendant to the operation of the device. The printing characters on the web W are related to the printing characters on the printing devices D and when a public utility bill is being printed the printing characters on the web will be the prices and extensions for the bill addressed from one of the printing devices D. It is therefore necessary that the sequence of the printing devices D and the sequence of the printing characters on the web W be similar. To insure this similarity, impressions are made on the web W from the printing devices D. 20 The impressions on the web will correspond to the sequence of the printing devices D and the sequence of the printing characters on the web W be similar. To insure this similarity, impressions are 25 made on the web W from the printing devices D. The impressions on the web will correspond to the sequence of the printing devices D and the sequence of the printing characters on the web W be similar. To insure this similarity, impressions are 30 made on the web W from the printing devices D. The impressions on the web will correspond to the sequence of the printing devices D and the sequence of the printing characters on the web W be similar. To insure this similarity, impressions are 35 made on the web W from the printing devices D. The impressions on the web will correspond to the sequence of the printing devices D and the sequence of the printing characters on the web W be similar. To insure this similarity, impressions are 40 made on the web W from the printing devices D. The impressions on the web will correspond to the sequence of the printing devices D and the sequence of the printing characters on the web W be similar. To insure this similarity, impressions are 45 made on the web W from the printing devices D. The impressions on the web will correspond to the sequence of the printing devices D and the sequence of the printing characters on the web W be similar. To insure this similarity, impressions are 50 made on the web W from the printing devices D. The impressions on the web will correspond to the sequence of the printing devices D and the sequence of the printing characters on the web W be similar. To insure this similarity, impressions are 55 made on the web W from the printing devices D. The impressions on the web will correspond to the sequence of the printing devices D and the sequence of the printing characters on the web W be similar. To insure this similarity, impressions are 60 made on the web W from the printing devices D. The impressions on the web will correspond to the sequence of the printing devices D and the sequence of the printing characters on the web W be similar. To insure this similarity, impressions are 65 made on the web W from the printing devices D. The impressions on the web will correspond to the sequence of the printing devices D and the sequence of the printing characters on the web W be similar. To insure this similarity, impressions are 70 made on the web W from the printing devices D. The impressions on the web will correspond to the sequence of the printing devices D and the sequence of the printing characters on the web W be similar. To insure this similarity, impressions are 75 made on the web W from the printing devices D.

In Fig. 10, a typical sheet is illustrated and the impressions X on this sheet are made from the printing devices D while the impressions X' are made from the web W. Since all of the impressions X are made before any of the impressions X' are made and as an independent set of stop fingers are employed to position the sheet to receive the impressions X' it is possible to locate

these impressions at the proper places on the stubs and main body portion of the sheet. The web W is held in position until the required number of impressions have been made therefrom, and further the mechanism is arranged to impart a step-by-step movement to the web. To attain this I arrange the web in a roll A', referred to hereinafter as the supply roll, and this roll is mounted on a spindle B' at the front of the machine. From the supply roll A' the web is directed over suitable guides to pass between the roller 52 and the platen P', an opening being provided in the table top intermediate the platen and the roller, and the web passes above this opening to a roller 73 mounted at the upper end of the bracket 74. The web W, platen P' and roller 52 and allied mechanisms are spaced from the platen P and cooperating mechanisms so that the first impression will not be made on a sheet from the web W until after the last impression has been made thereon from the printing device D. The stop fingers for positioning the sheet relative to the printing device D may be so located that the impressions may be made in any desired location on each of the stubs and on the main body portion, and the stop fingers for locating the sheet relative to the web W must also be located as required. Thus, when different style sheets are being printed impressions may be made thereon in accordance with the characteristics thereof, for the only change that need be made in the machine is the re-locating of the stop fingers and the operating cams therefor, and these parts are so mounted that they may be easily adjusted.

It has been stated that the sheets comprise a main body portion and one or more stubs and that impressions are made not only on the main body portion but also on each of the stubs. Consequently, it is necessary that each particular set of printing characters on the web W be retained in printing position until the required number of operations have been made therefrom. Thus, a step-by-step movement is imparted to the web W to unwind it from the supply roll A and to wind it on the takeup roll F that is mounted on the spindle E. The spindle E has a pulley 78 thereon and a pulley 80 is provided on the platen shaft 22. A belt 79 is directed about the pulleys 78 and 80 and serves to turn the takeup roll F to wind the web thereon.

The web is advanced so as to bring the windows into printing position and this is accomplished by providing spaced perforations in the web intermediate the windows. Pins 76 are provided at spaced intervals on the periphery of the roller 73 and these pins are spaced correspondingly to the spacing of the perforations 75 in the web W, so that the pins enter the perforations when the web is directed about this roller. From the roller 73 the web is directed about a guiding roller 77 from whence it extends to the takeup roll F. In order to advance the web with a step-by-step movement, the following mechanisms are provided: In the bracket 74 there is a shaft 81 having a disc 82 rotatably mounted thereon and a disc 83 fast thereon adjacent the disc 82. A gear 84 is also fast on this shaft. The gear 84 meshes with a pinion 85 fast on the shaft 86 which carries the roller 73. Pivotedly mounted on the shaft 81 is an arm 86 and pivotally connected to the medial portion thereof is a link 87, the free end of which is pivotally connected at 88 to the arm 65. Therefore, as the arm 65 is reciprocated in the manner described, the arm 75 86 is moved between the full and dotted line posi-

tions thereof illustrated in Fig. 3. Pivotedly mounted at the free end of the arm 86 is a pawl 89 (Fig. 7) acted on by a spring 90 to be urged into engagement with the periphery of the disc 82. Notches 91 (Fig. 8) are provided at equally spaced intervals in the periphery of the disc 82 and as many notches are provided as there are sections on the sheet to be printed. Consequently, when the arm 65 is reciprocated to bring about the printing operations, as previously described, the arm 86 and pawl 89 will be reciprocated and the amount of reciprocation imparted to the pawl will be slightly more than the spacing between the notches 91. As the arm 65 moves to the left in Fig. 3, the pawl 89 will be seated in one of the notches 91 and in the present instance where there are four such notches the pawl will move the disc 82 through a ninety degree angle. When the arm 65 moves to the right, as viewed in Fig. 3, the pawl 89 will disengage one of the notches 91 and will move rearwardly to seat in the succeeding notch. This movement will be carried out as each printing operation is performed but no movement will be imparted to the web W until the last section of the sheet is being printed which in the present instance will be the fourth section. The fourth notch 91' is deeper than the other notches 91, the bottom of these other notches 91 being arranged slightly outwardly of the periphery of the disc 83. In the disc 83 notches 92 are provided and the notch 91' is deep enough to align the bottom thereof with the bottom of the notches 92. Thus, during three operations of the pawl 89 it will seat in the notches 91 and no movement will be imparted to the disc 83. However, when the pawl 89 seats in the notch 91' it will also be seated in one of the notches 92 and therefore when the pawl 89 drives the disc 82 it will also drive the disc 83 and since the disc 83 is fast on the shaft 81, this shaft will also be turned. The ratio between the gears 84 and 85 is such that when the shaft 81 is turned, the roller 73 will be turned in an amount sufficient to move the web W so that one of the windows therein will be moved from alignment with the platen P' and the succeeding window will be moved into alignment therewith. In this manner a step-by-step movement is imparted to the web W and it is apparent that to vary the amount of movement imparted to the web it will only be necessary to change the ratio between the gears 84 and 85. To cause movement of the web at the proper time in the cycle of operation it is only necessary to provide discs such as the discs 82 and 83 with notches therein corresponding to the number of sections on the bill and by making these changes the device may be readily arranged to operate on any bill or sheet.

The operation of the device thus far described is as follows: Sheets having a permanent form printed thereon are introduced into the rack T and the machine is set in operation. The sheets are then successively withdrawn from the rack and passed to the conveyor belts 21 which carry the sheets along until the first of the stop fingers 29 is engaged by the leading edge of the first sheet whereupon the movement of the sheet is interrupted and at this time the platen P will operate to make an impression on the first section of the sheet from the printing device D which will have been previously moved into printing position over the anvil by the printing device feed mechanism 31. Immediately following this printing operation the first of the stop fingers 29 will be withdrawn from stopping position and the 75

sheet will again move with the conveyor belts and the second of the stop fingers will move into stopping position and the platen P will again be operated. The sheet will be stopped in this manner 5 as often as there are sections thereon and after the last section has been printed the sheet will move forwardly until the leading edge thereof engages the first of the stop fingers 29' and at this time the next sheet will move into engagement 10 with the first of the stop fingers 29. The platen P will make an impression from the next printing device D on the first section of this next sheet and the platen P' will make an impression from the printing characters on the web 15 W on the first section of the first sheet. Both sheets will then be released from the engaged of the stop fingers and will move into engagement with the succeeding of the stop fingers and this operation will be continued until the last section 20 of each sheet has been printed whereupon the first sheet will be discharged from the machine and the second sheet will be moved into position to be operated on by the platen P'. A third sheet will move into position to be operated on by the 25 platen P and the printing device D will be changed at this time. Prior to the time the first impression is made on the previously referred to second sheet, the web W will be advanced whereby impressions may be made from the printing 30 characters immediately behind those used in the printing operation on the first sheet. The foregoing operation is continued until as many sheets as desired have been printed.

In the embodiment of the invention thus far described, printing form for the additional variable data was changed each time a new sheet moved into printing relation with the platen P' and it has been shown that such an arrangement is particularly advantageous in printing prices 40 and extensions thereof on bills. However, under certain conditions it may not be desirable to change the printing form for the additional data as each new sheet moves into printing position with the platen P. An example of this is in the 45 printing of notices, such as are issued by insurance companies, whereupon the name and address of the agent is often printed as well as the name and address of the policy holder. The printing devices D are employed to print the 50 names and addresses of the policy holders but the agents' names are printed from other similar printing devices D' in a printing couple located similarly to that including the web W. When this is done the printing devices D having the names 55 and addresses of policy holders having the same agent are grouped and an identifying means is provided on the first printing device of a particular group. This identifying means may consist of a tab on the printing device or other analogous identifying means. When a printing device having such a tab moves into printing position means act on the tab to determine whether or not the printing device D' is to be changed. A mechanism for accomplishing this is disclosed in Figs. 11 to 60 15, inclusive, and by referring thereto it may be seen that a magazine M' is provided into which the printing devices D' may be introduced.

The printing devices D' are of the usual kind and if desired may be similar to the printing devices D. These printing devices are withdrawn 70 from the magazine M' and passed through a printing device guideway 90' to printing position below a platen P'' carried by the arm 91' pivotally mounted at 92 on the frame 16. On an extension of the platen shaft 22 is a cam 93

which engages a roller 94 on the arm 91 to urge the platen P'' into printing position, said platen being moved from printing position by a spring (not shown) or other suitable means. The printing devices are withdrawn from the magazine M' by a pair of pawls 95' pivotally supported on a slide block 96', mounted in the frame 16, and actuated in a manner described to withdraw the printing device from the magazine M' and pass them into printing position below the platen P''. In the application of Walter T. Gollwitzer, Serial No. 497,438, filed November 22, 1930, a printing device feed mechanism of the character employed herein is illustrated.

Heretofore, a printing device feed mechanism of this kind has been briefly described and as set forth, this printing device feed mechanism includes a drive rocker indicated by 95. The rocker 95 is mounted on a shaft 96 and on the bearing portion thereof is a boss 97 engaged by the nose 98 on the rocker 99 pivotally mounted at 100. At the free end of the rocker 99 is a bell crank 101 including an arm 102 to which a vertically extending rod 103 is pivotally connected. The upper end of the rod 103 extends through an opening 104 in the guideway for the printing devices D. If the printing device D in printing position is the first of a group it will be provided with a tab 105 and when the rod 103 is moved upwardly by reason of the engagement of the nose 98 with the boss 97 during operation of the rocker 95 said rod will move into engagement with the tab 105 and will be prevented from further upward movement. The rocker 99 will continue to move upwardly however and consequently the bell crank 101 will turn relative to the rocker 99. Connected to the arm 106 of the bell crank 101 is a link 107 which is also connected to one end of the lever 108 pivotally mounted at 109 on the frame 16. A spring 110 is connected to the lever 108 and to a spring anchor on the frame 16 and acts through the link 107 on the bell crank 101 to hold the rod 103 in its normal position. When the rod 103 engages a tab 105 to move the bell crank 101, the rod 107 is moved in the direction of the arrow 112 (Fig. 14). Consequently, the link 113' connected to the lever 108 is moved in the direction of the arrow 114 (Fig. 14). This link 113' is connected to a bar 113 and when the link is moved as just described the bar is withdrawn from position below the arm 115 of the bell crank 116 pivotally mounted at 117. The arm 115 includes a shield 118 and when said arm is rested on the bar 113 the pawl 119 is held in an upper position above the plane of the upper edge of the slide bar 120. However, when the bar 113 is withdrawn from below the arm 115 the shield 118 is moved from engagement with the nose of the pawl 119 at a predetermined time in the cycle of operation of the machine. This time is governed by a cam 121 on the cam shaft 27. This cam has a notch 122 therein into which the nose 123 on the arm 124 may move when the bar 113 is withdrawn from position below the arm 115, the notch 122 moving into registration with the nose 123 at a predetermined time in the cycle of operation of the machine. The slide bar 120 is connected to the slide block 96'. When this bar is moved the printing devices D' will be withdrawn from the magazine M', and this bar is operated when the nose 123 moves into the notch 122 for at this time the nose of the pawl 119 may move into the notch 124 in the slide bar 120. As soon as the pawl 119 is retracted from the notch 124, the spring 128' extending between the spring an-

chers on the frame and the slide bar 120 moves the slide bar back into its normal position. The pawl 119 is carried at the lower end of a rocker 125 (Fig. 12) pivotally mounted at 126 on a portion of the frame 13. This rocker 125 carries a roller 127 that engages a cam 128 fast on the shaft 22. Upon each revolution of the shaft 22 the cam 128 acts on the roller 127 to move the rocker 125 from the full line position of Fig. 12 into the dotted line position thereof, and when the pawl 119 is seated in the notch 124 the slide bar 120 will move therewith to thereby withdraw a printing device D' from the magazine M'. As soon as the printing device D having the tab 105 thereon moves from position above the rod 103, the spring 110 will act to urge the rod 103 upwardly and should there be no tab 105 in the path of the rod 103 said rod will move upwardly and the bell crank 101 will return to normal position. The spring 110 will also act on the lever 108 to urge the bar 113 into position below the arm 115 whereby the shield 118 will be positioned below the nose of the pawl 119 to move it from and hold it out of the notch 124. The rocker 99 may be moved under these conditions but, by reason of the pivotal connection between the arm 106 and the link 107, no movement will be imparted to the lever 106 until the rod 103 again engages a tab similar to the tab 105. Therefore, a printing device D' will not be withdrawn from the magazine M' unless the printing device D in printing position has a tab thereon.

The sheet S will be stopped by fingers similar to the fingers 29' to position it relative to the platen P'' so that impressions may be made on the sheet at proper places as has been previously described. When a printing device D' is withdrawn from the magazine M' by the pawls 95', the printing device engaged by the pawls will engage the printing device which has been disposed below the platen P'' and will move this printing device forwardly into alignment with the opening above the chute 129 and this printing device will fall through the chute into a suitable printing device receiving galley wherein the printing devices D' will be collected in the same sequence as that in which they were arranged when introduced into the magazine M'. If desired, the lower end portion 130 of the chute 129 may be arranged to be vertically extending whereby the printing devices will be collected therein in a vertical stack and when this is done a suitable retaining means will be provided to prevent the printing devices from falling from the end portion 130.

It is manifest that the device disclosed in Figs. 11 to 15, inclusive, will function to change a printing device D' only when the printing device D in printing position has a tab thereon and consequently if the printing devices D are arranged in a group all of the sheets printed from the printing devices D in a given group will receive impressions from the same printing device D'. Moreover, if each of the printing devices D is provided with a tab, this arrangement may be employed to successively change the printing devices D' and therefore an arrangement of this character may be used in the same manner as that employing the web W. Moreover, by providing a tail 131 on the pawl 89 and arranging this tail to cooperate with a bar similar to the bar 113, the advancing of the web W may be controlled from tabs on the printing devices D and such an arrangement is within the ambit of my invention.

I have described two embodiments of the invention, one employing a continuous web and a

5 stencil printing form and the other embodying individual printing devices. These individual printing devices may be of the type employing embossed printing characters or these printing devices may be of the stencil type. When printing devices using embossed characters are employed, a suitable inking means, such as an ink ribbon, will be passed thereover and when stencil printing forms are employed an inking device will be provided to supply ink thereto, and either of 10 these arrangements is within the purview of my invention. Furthermore, I have provided an arrangement wherein the printing devices employed in the auxiliary printing operation may be changed in synchronism with the printing devices used to change the first information or the printing devices for this auxiliary information may be retained in position until a number of printing impressions have been made therefrom, and I have described how the changing of the 15 printing devices used to print the auxiliary information may be regulated from the printing devices printing the main or first information. Furthermore, I have described two uses of the invention, namely, in the printing of utility bills 20 and in the printing of insurance notices but it is to be understood that these uses of the machine are merely illustrative and the machine is capable of being used for a number of other purposes which will be apparent to one skilled in 25 the art.

While I have illustrated selected embodiments of my invention it is to be understood that these are capable of variation and modification and I therefore do not wish to be limited to the precise 30 details set forth but desire to avail myself of such changes and alterations as fall within the spirit and scope of the following claims:

I claim:

1. In a printing machine, continuously operating means for moving a sheet through the machine, a printing means for making an impression on the sheet and including a series of changeable printing devices sequentially movable therethrough, means for interrupting movement of the sheet during the operation of the printing means, a second printing means spaced from the first printing means and operable to make an impression on the sheet after the sheet has moved from association with the first printing means, the second printing means including a series of changeable printing devices sequentially movable therethrough, means for interrupting movement of the sheet during operation of the second printing means, and means for operating the sheet movement interrupting means in timed relation with each other.

2. In a printing machine, continuously operating means for moving a sectional sheet through the machine, a printing means for making separate impressions on the sections of said sheet and including a series of changeable printing devices sequentially movable therethrough, means for interrupting movement of the sheet during the operation of the printing means, a second printing means spaced from the first printing means and operable to make separate impressions on the sections of said sheet in association with the impressions made on the sheet in the first printing means, the second printing means including a series of changeable printing devices sequentially movable therethrough, and means for interrupting movement of the sheet during the operation of the second printing means and positioned to stop the sheet relative 75

to the second printing means after the sheet has moved from association with the first printing means.

3. In a printing machine, continuously operating means for moving sectional sheets through the machine, a printing means for making separate impressions on the sections of said sheets and including a series of changeable printing devices sequentially movable therethrough, means for interrupting movement of the sheets during the operation of said printing means, a second printing means and spaced from the first printing means and operable to make separate impressions on the sections of said sheets as they are moved thereinto by the continuously operating means, the second printing means including a series of changeable printing devices sequentially movable therethrough, means for interrupting movement of the sheets during the operation of the second printing means, the sheet movement interrupting means for the first and second printing means being positioned relative to each other to so interrupt movement of the sheets that said printing means simultaneously operate on corresponding sections of successive sheets.

4. In a printing machine, means for moving a sheet therethrough, a printing means for making impressions on said sheet and including a series of changeable printing devices, a second printing means including another series of changeable printing devices for making impressions on said sheet, and means to position the sheet in the first printing means to receive an impression therein from one of the first series of printing devices and then to position the sheet in the second printing means to receive an impression therein from one of the second series of printing devices.

5. In a printing machine, means moving a series of printing devices therethrough, a platen, means moving a sectional sheet through the machine, means for interrupting movement of said sheet whereby said platen may make an impression on each section thereof, and printing means for making impressions on each section of said sheet and including another series of printing devices respectively related to the printing devices of the first series, and means for interrupting movement of said sheet to position the respective sections thereof in said printing means.

6. In a printing machine, means moving a series of printing devices therethrough, a platen for making impressions from said printing devices, means moving a sectional sheet past said platen, means for interrupting movement of said sheet to position the respective sections to receive an impression from a printing device of said series, printing means including a second series of printing devices, and other means for interrupting movement of said sheets to position the sections thereof in the printing means to receive an impression from a printing device in the second series related to the impressions made on the sections by said platen.

7. In a printing machine, a series of printing devices, a platen, means moving a sectional sheet past said platen, means for interrupting movement of said sheet whereby said platen may make an impression on each section thereof, printing means including a series of printing forms for making impressions on each section of said sheet related to the impressions made on the sections by said platen, separate means for advancing said printing devices and said printing forms in timed relation whereby impressions will be made on the

sections of said sheet from a printing form related to a particular printing device, and common means for operating said advancing means.

8. In a printing machine, means moving a series of printing devices therethrough, means moving a sheet through the machine, a platen for making impressions from said printing devices on the sheet, means interrupting movement of the sheet during operation of the platen, printing means including a series of printing forms and adapted to make impressions on said sheets related to the impressions made thereon by said platen, means for interrupting movement of said sheet during operation of the printing means, and means for advancing said printing forms in timed relation with the advancing of the printing devices whereby the relation of the impressions made from the printing devices to the impressions made from the printing forms may be maintained.

9. In a printing machine, means for moving a sheet therethrough, means sequentially moving printing devices through the machine, a platen for making impressions from the printing devices on the sheet moved through the machine, printing means for making impressions on said sheet related to the impressions made from the printing devices, and means for moving printing forms through the printing means in timed relation with the movement of the printing devices past the platen.

10. In a printing machine, means for moving a sheet therethrough, means sequentially moving printing devices through the machine, a platen for making impressions from the printing devices on the sheet moved through the machine, printing means for making impressions on said sheet related to the impressions made from the printing devices, and means for moving a web having printing characters thereon through the printing means in timed relation with the movement of the printing devices.

11. In a printing machine, means moving a sectional sheet therethrough, a platen, means moving printing devices through the machine into printing position below the platen, means for holding each of said printing devices in printing position until said platen has made impressions from one of said printing devices on the related sections of said sheet, printing means, and means moving printing forms through the printing means whereby said printing means may make impressions related to the impressions made from said printing devices on the related sections of said sheet.

12. In a printing machine, means moving a sectional sheet therethrough, a platen, means moving printing devices through the machine into printing position below the platen, means for holding each of said printing devices in printing position until said platen has made impressions from one of said printing devices on the related sections of said sheet, printing means, and means moving printing forms past said printing means and including means for holding the printing forms in printing position relative to said printing means until said printing means has made impressions on the related sections of said sheet.

13. In a printing machine, means for moving a sectional sheet therethrough, a platen, means moving printing devices through the machine into printing position below the platen, means for holding each of said printing devices in printing position until said platen has made impressions from one of said printing devices on the

related sections of the sheet printing means, means moving printing forms past said printing means and including means for holding the printing forms in printing position relative to said printing means until said printing means has made impressions on the related sections of the sheet, and common means for operating the printing device moving means and the printing form moving means in timed relation whereby a definite relationship between the impressions made from the printing devices and the printing forms may be maintained.

14. In a printing machine having two printing positions, means moving a sheet through the printing positions, separate means moving separate series printing devices into said printing positions, separate means making impressions from the printing devices moved into said printing positions, and means for stopping said sheet first in one printing position and then in the other whereby related impressions may be made on said sheet.

sheet.

15. In a printing machine, means successively moving sheets therethrough, a platen, means sequentially moving printing devices into printing position below said platen, means operating the platen, means operating in timed relation with the platen operating means for stopping the sheets whereby impressions may be made thereon from the printing devices by the platen, printing means, means operating said printing means from said platen operating means, means for moving printing forms through the printing means, and means for stopping said sheets whereby said printing means may make impressions thereon from said printing forms.

16. In a printing machine, means successively moving sheets therethrough, a platen, means sequentially moving printing devices into printing position below said platen, means operating the platen, means operating in timed relation with the platen operating means for stopping the sheets whereby impressions may be made thereon from the printing devices by the platen, printing means, means operating said printing means from said platen operating means, means for moving printing forms through the printing means, means for stopping said sheets whereby said printing means may make impressions thereon from said printing forms, and said printing means being spaced from said platen whereby said printing means will make impressions on the sheet after it has moved from operative relation with said platen.

55 17. In a printing machine, means successively
moving sheets therethrough, a platen, means se-
quentially moving printing devices into printing
position below said platen, means operating the
platen, means operating in timed relation with
60 the platen operating means for stopping the
sheets whereby impressions may be made there-
on from the printing devices by the platen, print-
ing means, means operating said printing means
from said platen operating means, means for
65 moving printing forms through the printing
means, and means for stopping said sheets where-
by said printing means may make impressions
thereon from said printing forms, said means
changing said printing devices and said printing
70 forms operating in timed relation whereby im-
pressions made by said printing means will be
related to the impressions made from said print-
ing devices.

18. In a printing machine, means successively moving sheets therethrough, a platen, means se-

quentially moving printing devices into printing position below said platen, means operating the platen, means operating in timed relation with the platen operating means for stopping the sheets whereby impressions may be made thereon from the printing devices by the platen, printing means including a printing member, an inking member, and means moving printing forms into position between said printing member and said inking member, means stopping the sheets 10 relative to said printing means, and means operable from the platen operating means for moving said printing member and inking member into printing relation with the printing form whereby impressions may be made on the sheets from said 15 printing form.

printing form. 19. In a printing machine, means successively moving sheets therethrough, a platen, means sequentially moving printing devices into printing position below said platen, means operating the 20 platen, means operating in timed relation with the platen operating means for stopping the sheets whereby impressions may be made thereon from the printing devices by the platen, printing means including a printing member, an inking member, 25 and means moving printing forms into position between said printing member and said inking member, means stopping the sheets relative to said printing means, means operable from the platen operating means for moving said printing member and inking member into printing relation with the printing form whereby impressions may be made on the sheets from said printing form, and said printing means being spaced from said platen whereby said printing means 30 will make impressions on the sheet after it has moved from operative relation with said platen. 35

29. In a printing machine, means successively moving sheets therethrough, a platen, means sequentially moving printing devices into printing position below said platen, means operating the platen, means operating in timed relation with the platen operating means for stopping the sheets whereby impressions may be made thereon from the printing devices by the platen, printing means including a printing member, an inking member, and means moving printing forms into position between said printing member and said inking member, means stopping the sheets relative to said printing means, and means operable from the platen operating means for moving said printing member and inking member into printing relation with the printing form whereby impressions may be made on the sheets from said printing form, said printing means being spaced from said platen whereby said printing means will make impressions on the sheet after it has moved from operative relation with said platen, said means changing said printing devices and said printing forms operating in timed relation whereby impressions made by said printing means will be related to the impressions made from said printing devices. 40 45 50 55 60 65 70 75 80 85 90

21. In a printing machine, means successively moving sheets therethrough, a platen, means sequentially moving printing devices into printing position below said platen, means operating the platen, means operating in timed relation with the platen operating means for stopping the sheets whereby impressions may be made thereon from the printing devices by the platen, printing means, means operating said printing means from said platen operating means, means for moving printing forms through the printing means, means for stopping said sheets whereby 75

said printing means may make impressions thereon from said printing forms, and means controlled from the printing devices for regulating the operation of the means moving the printing forms through the printing means.

22. In a printing machine which has two printing positions, means for moving a sheet through said printing positions, means moving printing devices through one of said printing

10 positions, means moving printing forms through the other of said printing positions, and means cooperating with each of said printing devices for controlling the movement of said printing forms as determined by the characteristics of

15 said printing devices whereby impressions made on the sheet from said printing forms may be maintained in a definite relation to the impressions made on the sheet from the printing devices.

20 23. In a printing machine which has two printing positions, means for moving a sheet through said printing positions, means moving printing devices having identifying means thereon through one of said printing positions, means

25 moving printing forms through the other of said printing positions, and selector means cooperating with the identifying means on the printing devices for effecting operation of the printing form moving means upon cooperation of the

30 selector means with predetermined of the identifying means whereby the impressions made from said printing forms may be maintained in a definite relation to the impressions made from said printing devices.

35 24. In a printing machine which has two printing positions, means moving sheets through said printing positions, means moving printing devices having identifying means thereon through one of said printing positions, means moving

40 printing forms through the other of said printing positions, and selector means cooperating with the identifying means on said printing devices for effecting the operation of the moving means for said printing forms upon cooperation

45 of the selector means with predetermined of the identifying means whereby one of said printing forms may be maintained in printing position until predetermined identifying means on one of said printing devices moves into a certain position

50 in the machine to thereby retain one of said printing forms in printing position until a number of impressions have been made therefrom onto sheets receiving impressions from the printing devices in advance of the printing device carrying said predetermined identifying means.

55 25. A printing means for a printing machine embodying an impression member, an inking member including an inking device, and means carrying printing forms and positioned between the impression and inking members, means for moving said impression and inking members into printing position to make an impression from the printing form positioned therebetween, means

60 for traversing said inking device over said form when the inking member is in printing position, and means carried by an operative part of the means traversing said inking device over said form and operable to impart a step-by-step movement to the means carrying said printing forms whereby said forms will be successively positioned between said impression and inking members.

65 26. A printing means for a printing machine embodying an impression member, an inking member, and means carrying printing forms and

positioned between the impression and inking members, means for moving said impression and inking members into printing position to make an impression from the printing form positioned therebetween, means for imparting a step-by-step movement to the means carrying said printing forms whereby said forms will be successively positioned between said impression and inking members, and means controlling the operation of said step-by-step movement imparting means whereby said printing forms may be retained between said impression and inking members for a predetermined number of successive operations of said impression and inking members and including a pair of ratchet wheels and a pawl 5 cooperating with said wheels, said ratchet wheels having an equal number of teeth therein, the teeth on one of said wheels being arranged to prevent the pawl from engaging the teeth on the other of said wheels between predetermined operations of the pawl whereby said pawl motivates said wheel simultaneously on other than said predetermined operations thereof.

20 27. A printing means for a printing machine embodying a pair of arms, a common pivot for 25 said arms, an impression member carried by one of said arms, an inking member carried by the other of said arms, means moving printing forms between said impression and inking members, a reciprocal member, means connecting said arms to said reciprocal member whereby said impression and inking members are moved toward and away from each other into printing position relative to a printing form positioned therebetween, and means for reciprocating said inking member 30 relative to said form when said inking member is moved into printing position.

25 28. A printing means for printing machines embodying a pair of arms, a common pivot for said arms, a platen carried by one of said arms, an inking means carried by the other of said arms, means moving platen forms between said printing and inking means, a reciprocal member, and links pivotally connected to said reciprocal member and to said arms and extended in a determined angular relation whereby operation of said reciprocal member varies said angular relation to move said arms toward and away from each other to make an impression from a printing form positioned between said platen and inking 35 means.

40 29. A printing means for printing machines embodying a pair of arms, a common pivot for said arms, a platen carried by one of said arms, an inking means carried by the other of said arms, 45 means moving printing forms between said platen and inking means, a reciprocal member, a link pivotally connected to one of said arms and said reciprocal member and normally extending at right angles to said reciprocal member, another link pivotally connected to the other of said arms and to said reciprocal member and normally extending at an acute angle to said reciprocal member, and means moving said reciprocal member to alter the direction of extent of said links 50 with respect to said reciprocal member to move said arms toward each other to make an impression from a printing form positioned between said platen and inking means.

45 30. In a printing machine which has two 70 printing positions, means for moving a sheet through said printing positions, means moving printing devices through one of said printing positions, means moving printing forms through the other of said printing positions, and means oper- 75

able on each cycle of operation of the machine for controlling movement of said printing forms from said printing devices and including a yieldable portion adapted to be held against movement to effect control of the movement of said printing forms.

31. In a printing machine which has two printing positions, means for moving a sheet through said printing positions, means moving printing devices through one of said printing positions, means moving printing forms through the other of said printing positions, and means for controlling movement of said printing forms and embodying a yieldable portion including a member engageable with identifying means on the printing devices for regulating operation of said yieldable portion to control the movement of said printing forms.

32. In a printing machine, a platen, a magazine adapted to receive a series of printing devices, a guideway for directing the printing devices from said magazine to printing position below said platen, means for moving printing devices through said guideway, said guideway having an opening therein intermediate the ends thereof, and means below said opening to receive a printing device moved from position below said platen upon movement of another printing device into position below said platen and including an inclined member disposed below said printing device guideway and terminating in a substantially vertically extending part adapted to direct printing devices passing through said opening to a storage member.

33. In a printing machine having a pair of printing positions, a platen at each of the printing positions, means for sequentially moving series of printing devices through each of said printing positions independently, an operating shaft, independent means on said shaft for operating said platens, and means for moving a sheet through said printing positions whereby said platens may successively operate to make impressions on said sheet.

34. In a printing machine having a pair of printing positions, a platen at each of the printing positions, means for sequentially moving series of printing devices through each of the printing positions independently, an operating shaft, independent means on said shaft for operating said platens, independent means operated by said shaft for operating the printing device moving means, and means for moving a sheet through said printing positions whereby said platens may successively operate to make impressions on said sheet.

35. In a printing machine having a pair of printing positions, a platen at each of the printing positions, means for sequentially moving independent series of printing devices through the printing positions, an operating shaft, independent means on said shaft for operating said platens, independent means operated by said shaft for operating the printing device moving means, means for moving a sheet through said printing positions whereby said platens may successively operate to make impressions on said sheet, and means operated by the operating means for one of the printing device moving means for controlling the operation of the means operating the other of the printing device moving means to thereby control movement of the series of printing devices moved through the machine by said other moving means.

36. In a printing machine having a pair of

printing positions, a platen at each of the printing positions, means for sequentially moving independent series of printing devices through the printing positions, an operating shaft, independent means on said shaft for operating said platens, independent means operated by said shaft for operating the printing device moving means, means for moving a sheet through said printing positions whereby said platens may successively operate to make impressions on said sheet, and means operated by the operating means for one of the printing device moving means and adapted to control the means operating the other of the printing device moving means to thereby control movement of the series of printing devices moved through the machine by said other moving means.

37. In a printing machine having a pair of printing positions, a platen at each of the printing positions, means for sequentially moving independent series of printing devices through the printing positions, the printing devices of one of said series having identifying means thereon, an operating shaft, independent means on said shaft for operating said platens, independent means operated by said shaft for operating the printing device moving means, means for moving a sheet through said printing positions whereby said platens may successively operate to make impressions on said sheet, and control means operated by the operating means operating the moving means for the series of printing devices having identifying means thereon and including means cooperating with the identifying means on said printing devices and adapted to control the means operating the other of the printing device moving means to thereby control movement of the series of printing devices moved through the machine by said other moving means.

38. In a printing machine having a pair of printing positions, a platen at each of the printing positions, means for sequentially moving independent series of printing devices through the printing positions, the printing devices of one of said series having identifying means thereon, an operating shaft, independent means on said shaft for operating said platens, independent means operated by said shaft for operating the printing device moving means, means for moving a sheet through said printing positions whereby said platens may successively operate to make impressions on said sheet, and control means operated by the operating means operating the moving means for the series of printing devices having identifying means thereon and including means cooperating with the identifying means on said printing devices and adapted to control the means operating the other of the printing device moving means to thereby control movement of the series of printing devices moved through the machine by said other moving means, said control means including parts capable of conjoint and relative movement and embodying a part operable to prevent operation of said other printing device moving means upon relative movement of said parts.

39. A printing couple adapted for use in a printing machine and including an impression member and means for moving printing devices into printing relation with said impression member, said moving means including a pair of discs mounted in side by side relation, one of said discs

being of smaller diameter than the other, each of said discs having notches in the periphery thereof, at least one of the notches in the periphery of the larger disc extending thereinto below the periphery of the smaller disc and the other notches in said larger disc terminating outwardly of the periphery of the smaller disc, a pawl successively engageable in the notches in the larger disc and adapted to engage a notch 5 in the smaller disc upon engagement of the pawl into a notch in the larger disc extending below

the periphery of the smaller disc whereupon the pawl engages notches in both discs, means operating said pawl in timed relation with the impression member whereby said pawl may drive said discs, said pawl driving the smaller disc only when it engages a notch in the periphery thereof, and means connecting the smaller disc to the moving means whereby the printing devices are advanced only upon movement of the smaller disc by said pawl. 5

HENRY E. HUBBARD.
